[57] CLAIM

The ornamental design for a water sports board, as shown and described.

DESCRIPTION

FIG. 1 is a front and top perspective view of a water sports board showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side thereof being a mirror image of the right side;

FIG. 7 is a cross sectional view thereof, taken along line 7—7 of FIG. 2;

FIG. 8 is a cross sectional view thereof, taken along line 8—8 of FIG. 4;

FIG. 9 is a cross sectional view thereof, taken along line 9—9 of FIG. 4; and

FIG. 10 is a cross sectional view thereof, taken along line 10—10 of FIG. 4.
